HANDRAIL POST BRACKET

Louis Blum, Pittsburgh, Pa., assignor to Blumcraft of Pittsburgh, Pittsburgh, Pa., a firm

Application December 29, 1958, Serial No. 53,946

Term of patent 14 years

(Cl. D13—7)

FIG. 1.

FIG. 2.

FIG. 3.

Fig. 1 is a perspective view of a handrail post bracket embodying my new design;

Fig. 2 is a perspective view taken from a position diametrically opposite that of Fig. 1; and

Fig. 3 is a cross sectional view taken along line III-III of Fig. 2.

I claim:

The ornamental design for a handrail post bracket, as shown.
